UNITED STATES PATENT OFFICE

FRANK C. DELI, OF CHICAGO, ILLINOIS, ASSIGNOR TO AUTOPOINT COMPANY, OF CHICAGO, ILLINOIS, A CORPORATION OF ILLINOIS

ADJUSTABLE PEN SUPPORT

Application filed March 31, 1931. Serial No. 526,673.

My invention relates to pen supports and more particularly to a pen support capable of lateral and vertical rotation about a fixed center post.

5 A common objection to pen supports is the relatively great cost of producing the same suitable for the purpose desired. An object of my invention is to provide a pen support including a socket, the majority of the parts 10 being stamped from a light gauge of metal, or, if desired, being molded in large number for economy.

A further object of my invention is to provide a construction which may be readily, 15 simply and economically assembled without the necessity of the use of any tools whatsoever.

A still further object is the provision of a device embodying the advantages above set forth, and capable of accurate adjustment relative to the degree of friction against the supporting post by a single means operable by 20 the pen socket. Thus by the simple action of turning the pen socket, any desirable adjustment of the parts will be effected.

My invention will be more readily understood by reference to the accompanying drawings in which:

Fig. 1 is a side elevation of a pen support 30 such as contemplated in my invention;

Fig. 2 is a vertical sectional view of the support shown in Fig. 1, showing the post contacting means in elevation;

Fig. 3 is a composite view showing the various parts of my invention, some being in 35 vertical section, and

Fig. 4 is a horizontal sectional view taken on the lines 4—4 of Fig. 1.

By reference to the drawings it will be seen 40 that I provide a base 10 having a central opening 11 therein for reception of a threaded bolt 12. The upper end of the bolt is headed to provide a flanged support 13, which is adapted to rest upon the base 10. Projecting upward from the support 13 and formed as a part thereof, is the post 14 having a circumferential groove 15 at substantially the middle thereof, and another groove 16 adjacent the lower extremity thereof.

45 As shown in Fig. 3 the assembly of the de-

vice contemplates the use of a pair of duplicate discs 17, which may be preferably stamped from a light gauge of metal, or molded if desired. The disc 17 is provided with a pair of inwardly extending ears 18 adapted to fit around the post 14 when applied thereto. I may also form a slight projection 19 within the curvature of the wings 18, which projection is adapted to lie inside the middle groove 15 of the post. When the discs are placed around the post it is found desirable to provide a semi-circular notch 20 in the lower periphery of the disc for reception in the groove 16, whereby to insure the locking of the disc against removal either by a laterally or vertically directed force.

After the duplicate discs are placed in position over the post, the duplicate cover discs 21 are placed thereover, the periphery of the cover discs being adapted to fit into the circular groove 22 on the face of the clamping discs and to utilize the same as bearings. The cover discs 21 have duplicate extensions 23 at one side which are formed in a semi-conical shape so that when the duplicate cover discs are placed over the discs 17 the extensions 23 contact and are substantially in cross section.

The cover discs 21 have the extremities thereof bent inward to provide projections 24 for cooperation with the opposite, parallel grooves 25 in the threaded stub shaft 26. Thus the shaft having parallel grooves adapted to receive the projections 24, is unable to rotate when the device is in operative position.

The next step in the assembly of the device of my invention comprises the inserting of the threaded portion of the shaft 26 into the lower threaded end 27 of the pen socket 28. The lower extremity of the socket 28 is provided with a metal ferrule 29 having an extending lip 30 adapted to bear against the conical portion 23 of the cover discs when the socket is screwed down over the shaft 26.

Thus it is readily seen with the parts assembled as described, the simple action of turning the socket 28 will serve to draw the ferrule 29 over the conical portion 23 of the cover discs 21, thus exerting a clamping ac-

100

tion against the discs 17 through the bearing grooves 22 which is transmitted to the post 14. In this manner the friction for both lateral and vertical movements of the cover 5 discs is effected at right angles to the object upon which the force is directed.

It is evident from the description that the various parts herein may be simply and readily manufactured by simple stamping operations 10 and the entire device may be quickly and easily assembled by hand without the use of any tools whatever.

Obviously modifications and variations 15 may be made in the device herein disclosed and I do not wish to be limited except as indicated in the appended claims.

I claim:

1. In a device of the class described, the combination of a support, a post thereon, a 20 pair of discs adapted to be clamped on the post and to rotate about the longitudinal axis of the post, a pair of cover discs adapted to overlie said clamping discs and to oscillate about the transverse axis of the post, a pen 25 socket, and screw means between the socket and cover discs adapted to effect clamping action of the cover discs on the clamping discs.

2. In a pen support, the combination of a 30 support, a post thereon a pair of discs adapted to be clamped on said post and to rotate about the longitudinal axis thereof, a pair of cover discs adapted to overlie said clamping discs and to oscillate thereon about the trans- 35 verse axis of said post, a pen socket and screw means between the socket and cover discs adapted to effect a clamping action of said cover discs on said clamping discs.

3. A pen support of the class described 40 comprising a support, a post thereon, said post having a circumferential groove between its ends, a pair of clamping discs adapted to be clamped over said post and to cooperate with the groove therein, said discs being 45 adapted to rotate about the longitudinal axis of the post, a pair of cover discs adapted to substantially overlie said clamping discs and to oscillate thereon about the transverse axis of said post, said cover discs having a pro- 50 jection thereon extending laterally from the margin thereof, a pen socket, and screw means between the pen socket and said projections on said cover discs whereby to effect a clamping action of said cover discs on 55 said clamping discs.

4. A pen support of the class described 60 comprising a support, a post thereon, said post having a circumferential groove between its ends, a pair of clamping discs adapted to be clamped over said post and to cooperate with the groove therein, said discs being adapted to rotate about the longitudinal axis of the post, a pair of cover discs adapted to substantially overlie said clamping 65 discs and to oscillate thereon about the

transverse axis of said post, said cover discs having a projection thereon extending laterally from the margin thereof, a pen socket, and screw means comprising a threaded stub shaft, having a pair of oppositely disposed, 70 transverse slots on one end between the pen socket and said projections on said cover discs whereby to effect a clamping action of said cover discs on said clamping discs.

In testimony whereof I have affixed my 75 signature.
